UNITED STATES PATENT OFFICE

WILLIAM STEININGER, OF BERWYN, ILLINOIS, ASSIGNOR TO W. D. ALLEN MANUFACTURING COMPANY, OF CHICAGO, ILLINOIS, A CORPORATION OF ILLINOIS

LAWN SPRINKLER

Application filed January 12, 1929. Serial No. 332,178.

This invention relates to lawn sprinklers and more particularly to lawn sprinklers including a rotatable sprinkler head mounted on a base, rotation of the sprinkler head being effected as an incident to the discharge of water from one or more nozzles.

An important object of the present invention is to provide a lawn sprinkler of the type above referred to in which the rotary element is mounted on the base in an improved manner so as to be freely rotatable.

Another important object of the invention is to provide means whereby the rotatable sprinkler head may be locked against rotation when desired so as to convert the rotating sprinkler to a stationary sprinkler.

Still another object of the invention is to provide an improved nozzle construction whereby the kind of stream discharged by the sprinkler may be adjusted to suit various requirements and also to provide a nozzle mounted on the rotatable sprinkler head in such a way that it may be readily adjusted to any desired position relative to the sprinkler head.

The invention also contemplates the production of a lawn sprinkler of the type above referred to at a minimum of expense while at the same time producing a high quality, neat appearing sprinkler, and in general, it is the object of the invention to provide an improved sprinkler of the class described.

Other objects and advantages of the invention will be understood by reference to the following specification and accompanying drawings in which I have illustrated a lawn sprinkler embodying a selected form of my invention.

In the drawings:

Fig. 1 is a side elevation.

Fig. 2 is a vertical section through the axis of the rotating sprinkler head and the base.

Fig. 3 is a section through the axis of one of the nozzles shown in Fig. 1.

Fig. 4 is a plan of a detail of construction shown also in Figs. 1 and 2, and

Fig. 5 is a view partly in elevation and partly in section corresponding to a part of Fig. 2, but showing a modified construction.

Referring now to the drawings, I provide

a base or skid member 10 having a hose coupling part 11 and a chamber housing 12 provided with an outlet opening 13. This base and its above described parts are well known in the art and, therefore, need not be more fully described in this application.

A tubular post member 14 is secured to the base by having its lower end portion threaded to fit corresponding threads in the outlet aperture 13 of the base as indicated at 15. The tubular post 14 extends upwardly from the base, as clearly shown in the drawings, and a hollow stem 16 is rotatably mounted in the tubular post, bearings 17 and 18 adjacent the upper and lower ends respectively of the tubular post being provided for so supporting the hollow stem. Adjacent its upper end, the hollow stem 16 is provided with a laterally outwardly projecting flange 19 which provides a downwardly facing, outwardly extending shoulder 20 which is adapted to engage the upper end of the tubular post 14 to position the stem in the post.

For preventing upward displacement of the hollow stem from the post, I provide the lower end portion of the hollow stem with a reduced end portion 21, thereby forming a downwardly facing seat or shoulder 22 adapted to receive an annular stop member 23, as clearly shown in Fig. 2. The stop member 23 extends laterally outwardly beyond the periphery of the stem 16 and overlaps the lower end portion of the post, as indicated at 24. The annular stop member 23 may be secured in place on the stem in any convenient manner and in the present instance, I find it convenient to provide the reduced end portion 21 of the stem of such length that a portion thereof may be swaged over the stop member as shown at 25.

The upper end of the hollow stem 16 is provided with screw threading 26 and a sprinkler head 27 including a downwardly projecting connecting boss 28, is mounted on the said upper end of the stem so as to be rotatably supported thereby. As shown in Fig. 2, the downwardly projecting boss 28 is bored out and provided with screw threading fitting the screw threading 26 on the upper end of the stem.

The sprinkler head 27 includes hollow arms 28' and 29 which communicate with the interior of the hollow stem 16 and which arms terminate at their outer ends in upwardly projecting end portions 30 and 31. Nozzles such as shown at 32 and 33 are mounted on the ends 30 and 31 respectively of the sprinkler head arms.

The nozzles 32 and 33 are preferably of an adjustable type so that various kinds of streams can be discharged by the sprinkler and the nozzles are preferably mounted on the respective arm ends in such a way that the nozzles may be adjusted to a plurality of angular positions with respect to the length of the sprinkler head arms 28' and 29 whereby the sprinkler head may be caused to rotate as an incident to the discharge of water from the nozzles.

In some instances, I find it desirable to prevent rotation of the sprinkler head 27 so that the streams discharged by the nozzles 32 and 33 may be directed continuously upon a predetermined area to be sprinkled. For locking the head against rotation, I provide a slidable pawl or locking device 34 which is slidably mounted in an opening 35 provided in a laterally outwardly extending flange 36 which is formed as an integral part of the post 14. One convenient manner of providing the opening 35 is to cut or otherwise form a crosswise extending notch or groove in the periphery of the flange 36. A wide ring-like member 37 is then slipped over the flange 36 so as to close the outer side of the said groove and the ring 37 may be anchored in place by indenting the same in one or more places, as indicated at 38. The locking device 34 is provided adjacent its upper end with a laterally inwardly projecting ridge-like boss or part 39 which is adapted to engage a milled or serrated periphery of the flange 19 of the rotatable stem 16. The lower end of the locking device 34 is bent outwardly to provide a flange or tab-like portion 40 for facilitating adjustment of the locking device into or out of engagement with the serrations of the flange 19. The inwardly projecting ridge part 39 also serves to prevent loss of, or accidental removal of the locking member 34 from the opening 35, the combined thickness of the projection 39 and member 34 being greater than the width of the opening 35. Obviously, the flange part 40 prevents removal of the locking member from the slot by upward movement in the slot.

For some purposes, I find it convenient to provide serrations such as shown at 41 (Fig. 5), in the periphery of the downwardly extending connecting boss 28 of the sprinkler head, such serrations being substituted for similar serrations provided in the flange 19 of the stem 16, as previously described.

When the serrations are provided in the boss

28 of the rotatable head, the stem 16 may be shortened by omitting the flange 19 so that the upper end portion of the stem will appear as shown at 16a in Fig. 5. Obviously, when the member 34 is slid upwardly into engagement with the serrations 41 in the boss 28 of the sprinkler head or into engagement with the serrations provided in the flange 19 of the stem, the sprinkler head will be locked against rotation. The arrangement is preferably such that when the locking pawl 34 is moved into engagement with the serrations, the pawl will be sprung outwardly slightly at its upper end so that there will be sufficient frictional engagement between the upper end of the pawl and the serrations, and between the pawl and walls of the opening 35, to maintain the pawl in such operative position of adjustment. When it is desired to unlock the sprinkler head, the pawl is merely pressed downwardly so that the upper end thereof is disengaged from the said serrations.

As shown in Fig. 5, the pawl 34 may be slidably mounted on a flange or boss 36a which projects laterally from the post 14 instead of in an annular flange such as flange 36 of Figs. 1 and 2. In this case, the outer end of the boss 36a is a flat surface provided with a recess for slidably receiving the pawl 34, and a plate 37a overlying the pawl, is secured to the boss so as to retain the pawl in the recess. Also, a pin such as shown at 67 may be provided for preventing the pawl from dropping downwardly through the recess. The pin eliminates the possibility of the projecting ridge 39 entering into the recess whereby the pawl might possibly become jammed in inoperative position.

The nozzles 32 and 33 may be of any conventional form, but I prefer to provide nozzles of the construction shown in Fig. 3. This construction includes a bent, hollow stem 42 having its lower end 43 rotatably fitting in or telescoping into, the upwardly projecting end of the arm, 31 in the present instance. The hollow stem 42 is provided with a laterally outwardly extending annular stop flange 44 which is adapted to be seated on the upper end of the part 31 of the arm, a gasket 45 of compressible material being preferably interposed so as to facilitate the provision of a water tight joint. A clamping nut 46 having an inwardly extending flange 47 overlying the flange 44 clamps the flange 44 towards the upper end of the part 31, it being understood that the clamping nut 46 is provided with internal screw threading 48 which is adapted to engage the external screw threading on the upper end of the part 31. Clamping action of the nut 46 is limited by engagement thereof with the end of the arm part 31, so that the gasket 45 is effectively compressed sufficiently to insure the provision of a water tight joint between

the bent stem part 42 and the end of the sprinkler arm while permitting rotation of the hollow stem in the opening of the part 31, while also serving to frictionally hold the 5 hollow stem in any desired fixed position of adjustment.

The upper end of the stem 42 is provided with a tip member 50 which is preferably shaped at its outer end as indicated at 51, 10 for a purpose which will presently appear. The tip member 50 is mounted on the outer end of the stem 42, preferably by means of a tubular tongue-like part 52 which fits in a counter bore 53 provided in the outer end of 15 the said stem. The tubular tongue 52 may be a drive fit in the counter bore 53 or it may be otherwise fixedly secured in place, for instance by means of soldering. The tip part 50 is bored out axially, as indicated at 20 54, and transversely as shown at 55, so that water may pass from the hollow arm 29 through the stem 42, through the bore 54 of the tip, and out through the transverse bore 55. Intermediate the transverse bore 55 and 25 the tubular tongue 52, the tip 50 is provided with an enlarged portion 56 having exterior screw threading 57 provided thereon.

A sleeve 58 provided with interior screw threading 59 is rotatably mounted on the tip 30 50, the screw threading 59 of the sleeve engaging the screw threading 57 of the tip so that by rotation of the sleeve, the same will be adjusted axially of the tip. The outer end portion of the sleeve is provided with an inwardly extending flange part 60 which cooperates with the shaped outer end 51 of the tip to control the kind of stream discharge from the nozzle. The opposite end of the sleeve 58 is provided with exterior screw 35 threading 61 which receives a packing nut 62 which serves to compress packing material 63 between the inwardly chamfered end 64 of the sleeve and the opposite wall 65 of the packing nut. The packing 63 prevents leakage out of the rear end of the sleeve and also serves to frictionally hold the sleeve 58 in the desired position of adjustment. The nozzle structure above described is such that each nozzle may be completely shut off by 40 screwing the sleeve downwardly on the tip until the inner edge of the flange 60 of the sleeve engages the tapered portion 66 of the tip. These parts, being preferably made of brass, will readily seat themselves so as to 45 form a substantially water tight joint. The construction shown is obviously very simple and easy to manufacture so that the cost of production is maintained at a minimum.

The above described sprinkler construction is, in its entirety, quite simple to manufacture, there being no complicated parts which require great skill to produce. I am aware that changes may be made in the form and construction of parts and in the manner 50 of assembling same, without departing from

the spirit of the invention, the scope of which should be determined by reference to the following claims, the same being construed as broadly as possible consistent with the state of the art. 70

I claim as my invention:

1. In a sprinkler of the class described, the combination of a stationary base part, a sprinkler head part rotatably mounted on said base, and a device axially slidably mounted on one of said parts and arranged to be adjusted to engage a portion of the other for locking said head part against rotation, said device and the engaged part being provided with means for effecting positive interlocking engagement therebetween. 75

2. In a sprinkler of the class described, the combination of a stationary base part, a sprinkler head part rotatably mounted on 80 said base, a device axially slidably mounted on one of said parts and arranged to be adjusted to engage a portion of the other for locking said head against rotation, the engaged part being provided with a plurality of circumferentially spaced serrations and said device having a portion shaped to fit and interlock with said serrations. 85

3. In a lawn sprinkler of the class described, the combination of a base, a tubular post extending upwardly from said base and provided adjacent its upper end with a laterally outwardly extending flange, said flange being provided with an opening extending therethrough adjacent its periphery 90 and substantially parallel to the axis of the post, a hollow stem rotatably mounted in said post and having spaced points of bearing engagement with said post, respectively located adjacent the top and bottom thereof, a 95 sprinkler head carried by said rotatable stem, a device mounted in the slot in said flange so as to be slidable axially of said post, said device being arranged to be adjusted to effect engagement of an end portion thereof 100 with a peripheral portion of one of said rotating parts, such part being provided with a plurality of circumferentially spaced serrations, and said end of said device being provided with an inwardly projecting part 105 adapted to interlock with said serrations. 110

4. In a sprinkler of the class described, a tubular member, a sprinkler head carried thereby, a base rotatably mounting said tubular member, said tubular member having irregularities formed on the outer wall thereof, and a latch member slidably carried by said base and engageable with the irregularities of said tubular member for positively locking said tubular member against rotation, said latch member being formed of resilient material, whereby a portion thereof may be sprung outwardly so as to engage said irregularities and will thereupon remain positively engaged therewith. 120 125 130
